Primary Examiner — Samantha Wood*Assistant Examiner* — Aula Soroush(57) **CLAIM**

The ornamental design for a toy for cats, as shown and described.

DESCRIPTION

FIG. 1 is a perspective view of a toy for cats showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is an enlarged perspective view thereof.

The broken lines illustrate portions of the toy for cats and form no part of the claimed design. The enlarged broken lines in FIGS. 1 and 9 represent the boundary of the enlarged portion of the toy for cats and form no part of the claimed design.

1 Claim, 9 Drawing Sheets(56)
